HOLDER FOR GOLFING ARTICLES

William Previdi, Allendale, N. J.

Application August 23, 1951, Serial No. 243,221

2 Claims. (Cl. 224—5)

1

This invention relates to new and useful improvements in a holder for golfing articles.

The present invention proposes the construction of a holder for golfing articles characterized by an attachment for suspension from the waist strap of a pair of trousers, a skirt or the like so as to conveniently support a plurality of golf tees, a score card and a pencil for marking the score card so that articles will be within convenient reach while out on a golf course playing a game of golf.

Still further, the present invention proposes characterizing the attachment by a main sheet having its top edge portion bent over the top of the strap and secured in position on the sheet in a manner to provide a tunnel through which the strap can be passed for mounting the attachment on the strap.

Another object of the present invention proposes several different ways for attaching the free edge of the bent over top edge of the main sheet to the main body thereof in a manner so that the size of the tunnel can be adjusted to fit straps of different widths or for making it possible to mount the holder in position on the strap or remove it therefrom without having to open the strap.

The present invention further proposes folding the bottom portion of the main sheet upward and securing it in position in a manner to provide a pocket for receiving a score card upon which a golfer can note the number of strokes required to play each hole of the golf course.

Still another object of the present invention proposes constructing the pocket so that one side thereof is divided off in a manner to receive a pencil to be used for marking the strokes upon the score card.

Another object of the present invention proposes several different types of holders for the pencils so that they will be conveniently available for marking the score cards.

A still further object of the present invention proposes the provision of a holder for golf tees on the main sheet characterized by an elongated strip of material stitched to the main sheet at spaced positions providing vertical passageways to receive the tees from the top thereof and support the same to be readily available by being lifted out of the top of the passageways.

As a further object, the present invention proposed conforming the passageways for the golf tees to the shape of the tees in a manner so that the material of the main sheet and the elongated strip of material will function to frictional-

2

ly grip the tees and hold them in position within the passageways.

It is a further object of the present invention to provide holders for golfing articles which are simple and durable, which are effective for their intended purposes and which can be manufactured and sold at reasonable costs.

For further comprehension of the invention, and of the objects and advantages thereof, reference will be had to the following description and accompanying drawings, and to the appended claims in which the various novel features of the invention are more particularly set forth.

15 On the accompanying drawings forming a material part of this disclosure:

Fig. 1 is a partial elevational view of a golfer having a holder for golfing articles in accordance with the present invention suspended from his waist strap.

Fig. 2 is an enlarged front elevational view of the holder, per se.

Fig. 3 is a rear elevational view of the holder, per se.

20 Fig. 4 is a vertical sectional view taken on the line 4—4 of Fig. 2.

Fig. 5 is a horizontal sectional view taken on the line 5—5 of Fig. 2.

Fig. 6 is a view similar to Fig. 1, but showing 25 the holder constructed in accordance with a modification of the present invention.

Fig. 7 is another view similar to Fig. 1, but showing the holder constructed in accordance with a further modification of the present invention.

Fig. 8 is a partial enlarged vertical sectional view taken on the line 8—8 of Fig. 7, but showing the snap fasteners in their disengaged position.

Fig. 9 is still another view similar to Fig. 1, but showing the holder constructed in accordance with a still further modification of the present invention.

Fig. 10 is a partial enlarged vertical sectional view taken on the line 10—10 of Fig. 9.

Fig. 11 is an elevational view similar to that shown in Fig. 2, but showing the holder constructed in accordance with a further modification of the invention and with the golf tees, score card and pencil removed.

Fig. 12 is an enlarged partial transverse sectional view taken on the line 12—12 of Fig. 11.

Fig. 13 is a developed view of the superimposed blanks of material used for forming the 55 holder shown in Figs. 11 and 12.

Fig. 14 is an enlarged partial transverse sectional view taken on the line 14—14 of Fig. 13.

The holder for golf articles, according to the first form of the invention illustrated in Figs. 1 to 4, includes a main sheet 20 of material depended from the waist strap 21 used for supporting a pair of trousers 22, see Fig. 1. If desired, the main sheet 20 can be depended from the waist strap of a lady's dress, pair of slacks or the like or from a separate strap worn expressly for supporting the holder.

The main sheet 20 has its top edge portion 23 bent over the top of the strap 21. In this first form of the invention, the top edge portion 23 is bent over the top of the strap 21 from the front to the rear and has its free edge secured to the rear face of the main sheet 20 by a single line of stitches 24 forming a tunnel 25 for the passage of the waist strap 21.

The bottom portion 26 of the main sheet 20 is folded forward and upward along the front face of the main sheet. The vertical side edges of the bottom portion are secured to the vertical side edges of the main sheet 20 by lines of stitches 27 forming a pocket for the score card 28. The junction of the bottom portion 26 with the main sheet 20 is reinforced by a line of stitches 29. The top edge 30 of the upwardly bent bottom portion 26 is folded downward and inward and secured in position by a line of stitches 31 finishing off the top edge of the pocket.

The main sheet 20 is provided with means for supporting a pencil 32 in position thereon to be conveniently available for marking the strokes of a game of golf on the score card 28. The pencil supporting means is provided by passing a vertical line of stitches 33 through the upwardly bent bottom portion 26 and the main sheet 20 closely adjacent one side of the main sheet. The line of stitches 33 divides the space between the main sheet 20 and the upwardly bent bottom portion 26 into one wider pocket 34 for the score card 28 and one narrower pocket 35 for the pencil 32. The pencil 32 is provided with a clip 36 by which the pencil can be secured to the top edge portion of the material of its respective pocket 35; however, if desired, the clip 36 can be omitted.

A holder is provided on the main sheet 20 for supporting a plurality of golf tees 37. The golf tee holder is comprised of a horizontally elongated strip of material 38 secured at its ends of the front face of the main sheet 20 above the top edge of the score card 28 by lines of stitches 39. Between its attached ends, the strip of material 38 is secured to the front face of the main sheet 20 by spaced lines of stitches 40 forming vertical passageways 41 for receiving the tees 37. As shown on the drawings, the tees 37 are substantially conical in shape and the lines of stitches 40, on opposite sides of the tees 37 are converged downward and inward. That causes the passageways 41 to be conformed to the shapes of the tees so that the adjacent faces of the main sheet 20 and the strip of material 38 will frictionally grip the tees 37 and retain them in position within the passageways until manually pulled from the top thereof. It is appreciated, however, that the lines of stitches 40 could be arranged parallel to each other and still provide suitable passageways 41 for receiving and supporting the golf tees 37.

The main sheet 20 and the strip of material 38 are formed of heavy duck material or other suitable cloth materials with the portions thereof stitched in position. If desired, the main sheet

26 and the strip of material 38 can be formed of rubber material with the portions thereof vulcanized in position or they can be made of a thermoplastic material with the portions thereof secured in position by heat sealing. Also, the frictional gripping of the golf tees 37 for the purpose of holding them in position within the passageways 41 can be improved by forming the strip of material 38 of an elastic material which will stretch when the tees are pushed into position from the tops of the passageways.

In the modification of the invention shown in Fig. 6, the score card 28' is a width substantially equal to the width of the main sheet 20 so that the upwardly bent bottom portion 26 of the main sheet 20 forms a single pocket 34' for containing the score card.

The holder for the pencil 32 in this form of the invention is comprised of a strip of material 45 which is elongated horizontally and secured along its top and bottom longitudinal edges to the front face of the main sheet 20 by lines of stitches 46. The strip of material 45 is located between the top edge of the score card 28' and the bottom ends of the golf tees 37 forming a horizontal passageway 47 for slidably receiving the pencil 32 from the one end thereof. The clip 36 of the pencil 32 is slipped into position on the strip of material 45 at the one end thereof to releasably retain the pencil in position.

In all other respects, the form of the invention shown in Fig. 6 is similar to that described in connection with Figs. 1 to 5 and like reference numerals are used to identify like parts.

The modification of the invention shown in Figs. 7 and 8 is characterized by a means for releasably securing the top edge portion 23' of the main sheet 20 in position on the rear face of the main sheet to be adjustable to straps 21 of different widths and to make it possible to mount the holder in position on the strap without having to open the same.

The releasable securing means comprises a horizontal row of spaced snap fasteners 50 mounted along the free edge of the top edge portions 23' of the main sheet 20. For each of the fasteners 50, there is a vertical spaced pair of complementary snap fasteners 51 mounted on the main sheet 20, see particularly Fig. 8. With this arrangement, it is merely necessary to pass the top edge portion 23' over the top edge of the strap 20 and to engage the snap fasteners 50 with the desired row of fasteners 51 depending upon the width of the strap 21. It is appreciated, of course, that the main sheet 20 could be provided with only a single row of complementary fasteners 51 for engagement by the fasteners 50 of the top edge portion 23'.

In all other respects, the form of the invention shown in Figs. 7 and 8 is also similar to that described in connection with the Figs. 1 to 5 and like reference numerals are used to identify like parts.

In the modification of the invention shown in Figs. 9 and 10, the free top edge portion 23'' of the main sheet 20 is folded outward and downward over the top edge of the strap 21 and has the strip of material 38' forming the holder for the golf tees 37 mounted on the front face thereof. A separable slide fastener 60 is used for releasably joining the free edge of the top edge portion 23'' to the front face of the main sheet 20 just above the top edge of the score card 28. The slide fastener 60 is controlled by a pull tab 61 and has one stringer 62 secured to the front face of

the main sheet 20 by a line of stitches 63. The other stringer 64 of the slide fastener 60 is secured to the free edge of the top edge portion 23" by a line of stitches 65. Thus, it is apparent that when the slide fastener 60 is completely open the holder can be put on and taken off without having to open the strap.

In all other respects, the form of the invention shown in Figs. 9 and 10 is similar to that described in connection with Figs. 1 to 5 and like reference numerals are used to identify like parts.

The modification of the invention shown in Figs. 11 to 14 is an exact duplicate of that shown in Figs. 1 to 5 except that the modified holder has its main sheet 20' formed of two superimposed layers of cloth material 70 and 71. The layers 70 and 71 are shown in Fig. 13 in their super-imposed positions prior to folding and stitching to complete the formation of the holder. The layer 70 is the outer of the layers and the layer 71 is the inner of the layers. The layers 70 and 71 are to be folded along the dot and dash line 72 to provide the bottom portion 26 which combines with the main portions of the layers 70 and 71 to form the pockets 34 and 35. The top edge portion 23 is to be folded down along the dot and dash line 72 to combine with the main portions of the layers 70 and 71 to form the tunnel 25 for the waist engaging belt.

As best shown in Fig. 12, the vertical side edges of the layers are turned under and secured in position by the lines of stitches 27 to form the vertical side edges of the pockets 34 and 35. To reduce the bulkiness in the outer bottom corners of the pockets 34 and 35, the inner layer 71 is formed at the ends of the fold line 72 with V-shaped cutouts 74 so that the inner layer 71 has no material in the outer bottom corners of the pockets 34 and 35.

In all other respects, the form of the invention shown in Figs. 11 to 14 is similar to that described in connection with Figs. 1 to 5 and like reference numerals are used to identify like parts.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. An attachment for a waist strap comprising an elongated main sheet provided with upper and lower portions, said upper portion being folded downwardly over the face of said sheet, said lower portion being folded upwardly over the face of said sheet, separable means fastening the free edge of said folded upper portion to said main sheet to form a channel for the passage of said waist strap, a horizontal strip secured at spaced positions to said folded upper portion to form therewith a golf tee holder, means securing the opposing sides of said folded lower portion to corresponding sides of said sheet to define a compartment, and means to secure said folded lower portion to said sheet along a longitudinal line intermediate said opposing sides to divide said compartment into a first pocket for accommodating a score card and a second relatively narrow pocket for accommodating a pencil.
2. An attachment for a waist strap comprising an elongated main sheet provided with upper and lower portions, said upper portion being folded downwardly over the face of said sheet, said lower portion being folded upwardly over the face of said sheet, a slide fastener releasably connecting the free edge of the folded upper portion to said main sheet to form a strap-receiving channel, a horizontal strip secured to the exposed face of said folded upper portion and stitched at spaced positions to form therewith a golf tee holder, said opposing sides of said folded lower portion being stitched to corresponding sides of said main sheet, said lower portion being additionally stitched to said main sheet along a line intermediate said opposing sides to define first and second pockets of unequal size for receiving a score card and a pencil, respectively.
